[57] CLAIM

The ornamental design for a barbecue grill, as shown and described.

DESCRIPTION

FIG. 1 is a perspective view of a barbecue grill showing my new design;

FIG. 2 is a side elevational view thereof, with the opposite side being a mirror image;

FIG. 3 is a front elevational view thereof;

FIG. 4 is a rear elevational view thereof;

FIG. 5 is a top view thereof;

FIG. 6 is a bottom view thereof; and

FIG. 7 is an enlarged perspective view thereof, showing the lid removed from the lower portion of the grill and suspended from the rear edge of the grill.
